UNITED STATES PATENT OFFICE.

IVAN ORNBERG, OF DETROIT, MICHIGAN, ASSIGNOR TO HUFF MOTOR CAR CORPORATION, OF DETROIT, MICHIGAN, A CORPORATION OF VIRGINIA.

DESIGN FOR A FRONT-BUMPER CONSTRUCTION.

Application filed May 28, 1928. Serial No. 26,879. Term of patent 3½ years.

To all whom it may concern:

Be it known that I, IVAN ORNBERG, a citizen of the United States of America, residing at Detroit, in the county of Wayne and State of Michigan, have invented a certain new, original, and ornamental Design for Front-Bumper Construction, of which the following is a specification, reference being had

therein to the accompanying drawings, forming part thereof, in which—

Fig 1 is a front elevation of the bumper; and Fig. 2 is a top plan view thereof.

I claim:

The ornamental design for a front bumper construction substantially as shown.

IVAN ORNBERG.
